UNITED STATES PATENT OFFICE.

HENRY K. PORTER, OF BOSTON, MASSACHUSETTS.

DESIGN FOR A WHIFFLETREE-COUPING.

SPECIFICATION forming part of Design No. 16,186, dated July 28, 1885.

Application filed May 2, 1885. Term of patent 14 years.

To all whom it may concern:

Be it known that I, HENRY K. PORTER, of Boston, in the county of Suffolk and State of Massachusetts, have invented and produced a new and original Design for Whiffletree Couplings or Centers; and I do hereby declare the following, when taken in connection with the accompanying drawing, to be a full, clear, and exact description of the same, and which said drawing constitutes part of this specification.

The accompanying drawing shows in perspective a whiffletree-coupling embodying my invention.

This invention relates to a design for the article of carriage hardware known to the trade as "whiffletree couplings or centers;" and it consists in the peculiar configuration of the coupling, as shown in the drawing.

In said drawing, A represents the upper or thin half or part of the coupling, and B represents the lower or thick half of the same. Each of said halves is formed with straight parallel edges *a a*, and with parallel top and bottom planes, *b b*, and ends *c c*, which are arcs

of a circle whose center is preferably the center of area of the coupling, as shown; and when these halves are united, as shown, the coupling presents the same configuration—that is to say, it has straight parallel edges, a straight top and bottom plane, which are parallel with each other, and ends which are arcs of a circle, as shown.

I hereby give notice that I have applied for Letters Patent of the United States for the improvement in whiffletree-couplings shown in the drawing in this application, said application having been filed February 17, 1883, Serial No. 85,377.

I claim—

The design for a whiffletree-coupling, consisting in a coupling of the shape shown, having the side lines, *a*, at each end thereof united by the arc-like lines *c*, as illustrated in the accompanying drawing.

HENRY K. PORTER.
